UNITED STATES PATENT OFFICE

HEINRICH A. W. PETERSEN, OF GARY, INDIANA

LIQUID-PUMP GOVERNOR

Application filed October 27, 1928. Serial No. 671,270.

The invention relates to governors, and particularly to those of the pressure regulated type and which are applicable to control a device such as a water pump, the regulator being under the control of the pressure created by the pump.

It is one of the prime objects of the invention to simplify the structure of a device of the character above referred to and to 10 provide a device which is effective and certain in operation.

It is another object to provide a governor which is hydraulically controlled.

It is a further object to provide a device of 15 the character above referred to with means for varying the degree of pressure necessary to cause the operation of the device and also to permit a nicety of adjustment to be accomplished.

20 It is a further object to combine a balance arm with a governor having the above characteristics, and to provide said balance arm with a chamber which the fluid to be regulated enters and from which it is discharged 25 in accordance with the pressure or resistance offered to the pump to thereby control the actuation of a valve which in turn controls a fluid such as steam which actuates the pump.

30 In addition to the above it is an object to connect the balance arm directly with the stem of the valve and to provide a connection between these parts which will allow freedom of motion between said parts and at all times 35 maintain the alignment of the valve and valve stem.

The invention will be explained in detail and more readily understood when read in conjunction with the accompanying drawings which illustrate one embodiment of 40 which the invention is susceptible, it being obvious that changes and modifications may be resorted to without departing from the spirit of the appended claims forming a part 45 thereof.

In the drawings, Fig. 1 is a sectional view of a governor constructed according to one embodiment of the invention.

Fig. 2 is a section taken on line 2—2 of Fig. 1.

Fig. 3 is a perspective view of the valve employed in the structure illustrated in Fig. 1, and

Fig. 4 is a plan view of the balance arm above referred to.

The structure illustrated contemplates the use of a valve casing 10 having an inlet opening 11 whereby the device may be connected through the medium of pipe connections to a steam boiler (not shown). This casing is further provided with an outlet passage 12 which may be connected to a steam actuated water pump. A valve 13 is arranged in the passage between these openings for the purpose of controlling the passage of steam from said boiler to the pump. The valve 13 is slidably arranged in an opening 14 which communicates with the passage 12. This valve is of the piston type and has one end thereof provided with a plurality of openings 17—17 and the opposite end formed to provide a cylinder, this last mentioned end and the opening preventing and permitting the passage of fluid therethrough, depending upon the position of said valve. The cylindrical portion of the valve allows of adjustments of the valve without causing it to assume an open position. A valve stem 18 extends from one end of said valve 13 and extends through the member 19 which provides a closure for the valve casing. This closure has its opposite ends threaded to permit it to be connected to the valve casing 10 and to allow the support or bracket 20 to be associated with said casing. The support 20 is threaded connected to the closure and said support is constructed to provide a means whereby the balance arm 22 may be connected to the remainder of the structure, and is further designed to provide a guide for

the valve stem 18, and to also support the coil spring 23 which surrounds the stem and reacts between an end of the support and the collar 24, the latter being under the direct control of the adjusting nut 26, which is threaded upon the end of the valve stem and provides a means whereby the pressure necessary to actuate the device may be varied. The balance arm 22 is pivoted to the support at 27 and is provided at one end with a weight 28, and has a chambered member 29 mounted upon the opposite end thereof, and is connected intermediate its ends to the valve stem 18 through the medium of the links 30—30, which are respectively connected to the balance arm at 31 and to the stem at 32, the last mentioned end of the links being attached to the cross member 33 secured to said stem. The coiled spring 23 and the adjusting nut provided upon the valve stem provide a simple and convenient means for controlling the pressure at which the valve is permitted to operate. This spring is of an expansion type and will therefore, when under compression, tend to assist the chambered member in causing the operation of the valve, and also provides a means for allowing the arm which carries the chamber and the weight to be adjusted toward and away from its center of gravity. It is therefore manifest that the mechanism is capable of adjustment so that it is operable to allow the opening of the valve upon a slight or great reduction of pressure or resistance, depending upon desire or necessity. It is obvious that when the spring is under compression a slight reduction of pressure throughout the system and in the chamber will permit the operation of the valve, also that when the spring is entirely released of its compression that a greater resistance is offered to the weight provided upon the opposite end of the arm, which will necessarily require a greater reduction of pressure in the chamber before the operation of the device can take place.

As before stated, the balance arm is connected with the links 30—30. To permit of this connection the balance arm is provided with the lateral projections 34 which are inserted in apertures provided in said links. The balance arm is further provided with the elongated opening 35 through which the valve stem is passed. The opening allows the balance arm to move freely upon its pivot and eliminates the possibility of contact between the valve stem and the arm, which will thus eliminate any binding of the parts and consequent interference with the freedom of operation of the structure.

The chambered member 29, which is mounted adjacent one end of the balance arm 22, has a flexible tubular member 36 extending therefrom, which may be connected to the water discharge passage of the pump or the bottom of the tank into which the water is

pumped by said pump. The tubular connection 36 will therefore provide a means whereby a pressure corresponding to the pressure existing in the tank or passage leading from the pump to the tank will be caused to exist in the chambered member carried by said arm, which pressure will vary in accordance with the pressure existing in the tank or passage leading from the pump to the tank as the case may be, and will therefore either cause the chambered member to overbalance the weight 28 and close the valve, or permit the weight to overbalance the chambered member and cause the valve to open. It is evident from an inspection of Fig. 1 that when the chambered member is partially filled the weight thereof will maintain the valve in closed position, in which condition it will remain until the pressure recedes, after which the chambered member will be overcome by the weight at the opposite end of the arm, raise the chambered member and open said valve.

My improved pump governor may be located or positioned without reference to the water tank when the same is used in connection with an air or steam tight tank but when the governor is used in connection with an open tank it must be located below the tank. From the above it will be noted that as the water rises in the tank the air pressure in the chambered member 29 is increased and when the water in the tank reaches a predetermined level the pressure or weight of the water in the tank forces some of the water through the conduit 36 into the chambered member 29. Thus it will be readily understood that the pressure of the water in forcing the water into the chambered member 29 is the element which controls the actuation of the governor.

From the foregoing explanation of the structure and operation of the device it is evident that a simple, effective and accurate structure is provided, which may be adjusted so as to control the degree of pressure necessary to cause the operation of the structure.

Having thus described my invention what I claim and desire to cover by Letters Patent is:

1. In a regulator, the combination of a valve casing, a valve having a stem, said valve being arranged in the casing and said stem being projected beyond the casing, a bracket secured to the casing, said stem being slidably held by said bracket, a lever pivoted to the bracket, a link connecting said lever with the valve stem, and gravity actuated pressure controlled means for controlling the operation of said valve, and means for varying the pressure at which said valve is operable.

2. In a regulator, the combination of a valve casing, a valve having a stem, said valve being arranged in the casing and said stem being projected beyond the casing, a bracket secured to the casing, said stem being slidably

- held by said bracket, a lever pivoted to the bracket, a link connecting said lever with the valve stem, and gravity actuated pressure controlled means for controlling the operation of said valve, means for varying the pressure at which said valve is operable, said last mentioned means including a spring, and means for varying the tension of said spring.
5. In a regulator, the combination of a valve casing, a valve having a stem, said valve being arranged in the casing and said stem being projected beyond the casing, a bracket secured to the casing, said stem being slidably held by said bracket, a lever pivoted to the bracket, a link connecting said lever with the valve stem, gravity actuated pressure controlled means for controlling the operation of said valve, means for varying the pressure at which said valve is operable, said last mentioned means including a spring arranged upon the valve stem and reacting between the bracket, and an adjustable means provided upon said stem for varying the tension of said spring.
10. In a regulator, the combination of a valve casing, a valve having a stem, said valve being arranged in the casing and said stem being projected beyond the casing, a bracket secured to the casing, said stem being slidably held by said bracket, a lever pivoted to the bracket, a link connected to said lever and to said valve stem, a chambered member arranged upon one end of the lever, and variable means mounted on said lever outside said casing and co-operating with said chambered member for controlling the operation of said valve.
15. In a regulator, the combination of a valve casing, a valve having a stem, said valve being arranged in the casing and said stem being projected beyond the casing, a bracket secured to the casing, said stem being slidably held by said bracket, a lever pivoted to the bracket, a link connecting said lever with the valve stem, a chambered member positioned on one end of said lever, a flexible conduit communicating with the interior of said member and adapted to be connected to the discharge passage of a pump for conducting fluid under pressure from said pump to the chambered member in a manner to enter and compress the air in said member, and adjustable means positioned on the opposite end of said lever and co-operable with said member for controlling the operation of said valve.
20. In testimony whereof I have signed my name to this specification, on this 26th day of September, A. D. 1923.
